Inventor:
Robert W. Uhlig
by John Hinealy,
His Attorney,

UNITED STATES PATENT OFFICE.

ROBERT W. UHLIG, OF ST. LOUIS, MISSOURI.

DIAMOND-HOLDER.

1,329,865.

Specification of Letters Patent.

Patented Feb. 3, 1920.

Application filed August 11, 1919. Serial No. 316,710.

To all whom it may concern:

Be it known that I, ROBERT W. UHLIG, a citizen of the United States, residing in the city of St. Louis and the State of Missouri, have invented a new and useful Improvement in Diamond-Holders, of which the following is a full, clear, and exact specification, reference being had to the accompanying drawings, which form a part 10 thereof.

My invention relates to devices for holding diamonds and similar hard substances when they are used in industrial work for the purpose of cutting or grinding; and my 15 invention relates particularly to those holders for diamonds used for the purpose of dressing or truing emery-wheels or similar grinders.

Heretofore it has been common to mount 20 the diamonds used for truing grinding wheels in the cavity of a holder by pouring a matrix in the cavity around the diamond. This matrix is usually at a high temperature when in a liquid condition, and therefore it tends to injure the diamond. It has also been common to mount the diamond in a holder by shrinking around it a body of metal, but this method tends also to crack or otherwise injure the diamond, and hence 25 it is objectionable. A further objection to the methods heretofore used lies in the fact that after a diamond has been mounted in its holder it is difficult to remove it without injuring the stone when it is desired to 30 remove it or to change the position of the diamond in the holder.

The object of my invention is to provide a holder for a diamond or similar object, which will admit of the diamond being 35 easily and quickly mounted therein in such a way as to firmly hold the diamond in place and which will also admit of the diamond being readily removed or remounted.

My invention is fully shown in the accompanying drawings where similar letters are used to designate similar parts. Figure 1 shows a view of one form of holder having a diamond mounted in it; Fig. 2 is a longitudinal section of the holder in Fig. 1, showing the internal arrangement of the holder with the diamond in place; Fig. 3 is a view of a form of holder embodying my invention; Fig. 4 is a longitudinal sectional view of a holder of Fig. 3, showing the arrangement of the parts with the diamond in place.

Referring to the figures, A is the body or

handle portion of the holder which has at one end a threaded part B. C is a cap provided with internal threads adapted to engage the threads formed on the part B. The 60 diamond Y is held by a holding member which comprises the jaws D and E. In Fig. 2 the threaded part B is shown as made integral with the body A; while in Fig. 4 the threaded part B is made integral with the 65 jaw E and is screwed into a socket formed in the body A. The jaws D and E are preferably made of copper or some similar soft metal. These jaws are formed by putting together the parts of metal of which they 70 are made and holding them tightly together and then boring a central opening U, which may extend from end to end as in Fig. 2 or only a part of the length of the jaws as in Fig. 4. I find it convenient to provide the 75 jaws with a pin G which is fixed in one of the jaws but which is loose in a hole formed in the other jaw; and I also find it advisable to solder together the jaws by, preferably, some form of solder having a low 80 melting point. After, however, the two pieces of metal, of which the jaws are to be formed, have been secured together and the central opening U formed, they are then turned so as to have an exterior surface F 85 which is the frustum of a cone. After the jaws have been turned so as to give them the desired conical shape, the solder or other fastening means is removed so that the jaws are separate and distinct one from the other. 90 The cap C is provided with an internally formed tapered, cone shaped surface adapted to engage with the surface F of the jaws. The jaw D in Fig. 4 rests on the shoulder H formed at the base of the jaw E on the 95 threaded part B, and is thus prevented from being moved axially of the holder, so that when the cap C is screwed down on B both jaws are forced up into the cap and are thereby clamped together firmly without being moved axially. In Fig. 2 both jaws D and E rest upon the upper end of the threaded part B and are simultaneously clamped together and fastened to the body portion 100 without being moved axially when the cap C is screwed in place. J is a lock nut which may be provided on the portion B, and K is a faceted portion which may be formed on the lower end of the cap C in order to facilitate screwing the cap in place. 105

When a diamond is to be mounted it is placed in the central opening U between the

jaws D and E and then the jaws are positioned on the holder and the cap C placed over them and screwed down tight so as to force the diamond into the metal as shown in Figs. 2 and 4. The opening U is, preferably, made to suit the diamond to be held so that the jaws are substantially in contact when the diamond is firmly mounted in the holder, and so that the ends of the jaws are also substantially flush with the end of the cap when the cap is screwed down as tight as is required.

It is evident that the size of the jaws and the taper of their exterior surface may be varied to suit different requirements without departing from the spirit of my invention, and that the method of making the jaws may be different from that herein described when it may be necessary or desirable.

What I claim as new and desire to secure by Letters Patent, is:

1. A diamond holder comprising a body portion, oppositely disposed jaw members adapted to be moved to and from each other without moving axially, each of said jaws being formed of metal into which said diamond can be embedded by pressure and having adjacent its outer end an exterior tapered surface and having a centrally disposed groove extending downwardly from said outer end, and a cap adapted to fit over said jaw members and having an interior surface adapted to engage with the tapered surfaces of said jaws whereby said jaws are forced together to hold said diamond embedded in the walls of said grooves.

2. A diamond holder comprising a body portion, oppositely disposed jaw members adapted to be moved to and from each other without moving axially, each of said jaws being formed of metal into which said diamond can be embedded by pressure and having adjacent its outer end an exterior tapered surface and having a centrally disposed groove extending downwardly from said outer end, a guide pin attached to one jaw member and projecting into a hole formed in the opposite jaw member, and a cap adapted to fit over said jaw members to engage with the tapered surfaces thereof whereby said jaws are forced together to hold said diamond embedded in the walls of said grooves.

3. A diamond holder comprising a body portion having its outer end formed substantially at right angles with the axis of said body portion and having exterior screw threads adjacent said end, oppositely disposed jaw members formed of a metal into which said diamond can be embedded by pressure, each of said jaw members having a tapered exterior surface adjacent its outer end and a centrally disposed groove extending downwardly from said outer end, and said jaw member being disposed with its inner end resting on the outer end of said body portion, a cap adapted to fit over said jaw members and having interior threads adjacent its inner end adapted to engage with the threads formed adjacent the outer end of said body portion and having adjacent its outer end an interior surface adapted to engage the tapered surfaces of said jaw members whereby when said cap is screwed onto said body portion said jaws are caused to move toward each other to hold said diamond embedded in the walls of said grooves.

4. A diamond holder comprising a body portion having its outer end formed substantially at right angles with the axis of said body portion and having exterior threads adjacent said outer end, oppositely disposed jaw members formed of metal into which said diamond can be embedded by pressure, each of said jaw members having a tapered exterior surface adjacent its outer end and a centrally disposed groove extending downwardly from said outer end and said jaw member being disposed with its inner end resting on the outer end of said body portion, a guide pin attached to one jaw member and projecting into a hole formed in the opposite jaw member, and a cap adapted to fit over said jaw members and having interior threads adjacent its inner end adapted to engage with the threads formed adjacent the outer end of said body portion and having adjacent its outer end an interior surface adapted to engage the tapered surfaces of said jaws whereby when said cap is screwed onto said body portion said jaws are caused to move toward each other to hold said diamond embedded in the walls of said grooves.

In witness whereof I have signed my name to this specification.

ROBERT W. UHLIG.
